(57) **CLAIM**

The ornamental design for an electrode for electric field therapy as shown and described.

DESCRIPTION

- 1.1 : Perspective
- 1.2 : Front
- 1.3 : Back
- 1.4 : Top
- 1.5 : Bottom
- 1.6 : Left
- 1.7 : Right

The dashed broken lines depict portions of the electrode for electric field therapy that form no part of the claimed design. The dashed-dot broken lines depict the bounds of the claimed design and form no part thereof, and the portions of the article within the boundaries form no part of the claimed design.
